CLAIM

The ornamental design for a brassiere as shown and described.

DESCRIPTION

FIG. 1 is a perspective view of a brassiere worn on a body model showing the new design;

FIG. 2 is a front view thereof;

FIG. 3 is a rear view thereof;

FIG. 4 is a left side view thereof;

FIG. 5 is a right side view thereof;

FIG. 6 is a perspective view showing a front piece of the brassiere unbuckled;

FIG. 7 is a front view of the brassiere not worn on the body model; and,

FIG. 8 is a rear view of the brassiere not worn on the body model.

The broken lines represent the portions of the design that form no part of the claim. The broken lines in FIGS. 1–6 showing a body model depict environment and form no part of the claim.

1 Claim, 8 Drawing Sheets
